UNITED STATES PATENT OFFICE

HAROLD B. WALLIS, OF DAYTON, OHIO, ASSIGNOR, BY MESNE ASSIGNMENTS, TO
FRIGIDAIRE CORPORATION, A CORPORATION OF DELAWARE

REFRIGERATING APPARATUS

Application filed January 31, 1927. Serial No. 164,712.

This invention relates to refrigerating apparatus, particularly to cooling units for refrigerating cabinets.

One of the objects of the invention is to provide an improved cooling unit which will be economical to manufacture and assemble.

Another object is to provide an improved cooling unit having a large ice freezing capacity.

10 Still another object is to provide a simple and economical arrangement of refrigerating ducts which provide a freezing space, with or without a cooling space surrounding the freezing space, and means for withdrawing heat from the interior of the freezing space.

Further objects and advantages of the present invention will be apparent from the following description, reference being had to 20 the accompanying drawings, wherein a preferred embodiment of one form of the present invention is clearly shown.

In the drawings:

25 Fig. 1 is a front view of a cabinet, having a door open, showing a cooling unit inside constructed in accordance with my invention;

30 Fig. 2 is a vertical section through a portion of the cabinet, showing the cooling unit on an enlarged scale;

Fig. 3 is a front elevation of a cooling unit; and

Fig. 4 is a side view of the same.

Referring particularly to Figs. 1 and 2, the 35 interior of the cabinet 10 is divided into a refrigerating compartment 11 and a food storage compartment 12 by an L-shaped partition 13, having openings 15 and 16 to permit circulation of air. The refrigerating compartment contains an evaporator or cooling unit, generally denoted by 18, to which refrigerant is supplied by a pipe 19 and from which it is withdrawn through a pipe 20 by 40 means of any suitable refrigerating apparatus (not shown). Such apparatus may be placed at any convenient location, such as in a machine compartment, provided with doors 21 beneath the storage compartment 12.

50 Air, cooled by the evaporator 18, descends

through opening 16 into the food compartment, displacing the warm air therein, which latter flows into the refrigerating compartment through the opening 15. This sets up a circulation of air and maintains the storage 55 compartment cold in the well known manner.

In accordance with my invention, I construct the cooling unit as follows:

An elongated header or boiler 22 for containing refrigerant is provided with ducts 23 depending and extending laterally from it to enclose an elongated horizontally disposed freezing space 24. Other ducts 25 depend from the header and extend laterally beyond the ducts 23 so as to be exposed to 60 and cool effectively the air circulating through the refrigerating compartment.

Considerable manufacturing advantage results from joining each of the ducts 23 to a duct 25 by connecting ducts 26, that is 65 making a single loop of pipe serve as one duct 23 and one duct 25. Preferably all the loops are of an identical shape, which is 70 asymmetrical to the central axial plane of the header. In assembling, alternate loops 75 are reversed, so as to alternate ducts 23 and 25 along the header. Bracing means for the loops are provided at the lower ends thereof and are in the form of strips 36 connected with the ducts 26.

80 Since the freezing space is of considerable volume, I provide means for dividing the freezing space into a plurality of freezing zones or compartments or for withdrawing heat from the interior of the space, in the 85 form of one or more refrigerant ducts 30 extending from the boiler into the center of the space with the horizontal portions extending longitudinally of and within the 90 space. One of the ducts 30 is located outside of the other of said ducts so that the inner duct is nested within the outer duct. As shown in Figs. 3 and 4, such ducts are 95 preferably loops, each connected to the header near each end of the header, and lying in its central axial plane.

In the freezing space are placed a number 100 of thermally conducting supports or shelves 31, some of which are arranged side by side as shown in Fig. 3, for receiving ice trays 35,

shown in Fig. 2. The longitudinally disposed ducts 30 divide the freezing space 24 into a plurality of freezing compartments bounded on one side by the ducts 23 and on the other side by the ducts 30. The shelves are thermally connected both with the ducts 23 and 30. This arrangement may be effected either by soldering rectangular metal sleeves 32 to the ducts 23 and 30, or by laying a shelf 31a on slides or brackets 34, which are soldered to the ducts. Both are shown in Fig. 3, two shallow sleeves 32 being used to receive individual shallow trays, and one deep sleeve 32a being used to receive either two shallow trays (as shown in Fig. 2) or, by removing the shelf 31a, one deep tray.

It will be seen from Fig. 4 that the ducts 30 have a relatively large portion of their surface in thermal contact with the sleeves. This arrangement enables me to provide a relatively large heat exchange area for withdrawing heat from the interior of the freezing zone by the use of a relatively small number of conduits. This effects a considerable saving in manufacture, as it requires neither a large number of loops of pipe, nor a large number of connections to the header, the latter especially being expensive manufacturing operations. I am thus enabled to produce economically a cooling unit, having a compact freezing space or zone or a plurality of freezing zones or compartments of large ice freezing capacity, surrounded by a zone which effectively cools the circulating air to refrigerate a storage compartment.

While the form of embodiment of the present invention as herein disclosed, constitutes a preferred form, it is to be understood that other forms might be adopted, all coming within the scope of the claims which follow.

What is claimed is as follows:

1. Refrigerating apparatus comprising, a header for containing refrigerant, a plurality of ducts extending from the header to form a freezing zone, and one or more ducts extending from the header and passing through the freezing zone in a direction transverse to the direction of the first mentioned ducts.

2. Refrigerating apparatus comprising, an elongated header for containing refrigerant, a plurality of ducts extending from the header transversely to its axis and forming a horizontal and rearwardly extending freezing zone, and one or more conduits connected to the header and extending rearwardly through the freezing zone.

3. Refrigerating apparatus comprising, an elongated header for containing refrigerant, one or more ducts extending from the header in an axial plane, a plurality of ducts extending from the header transverse to its axis and forming a freezing zone around the first mentioned ducts, and two or more supports in the freezing zone, the outer portion of each of the supports being thermally connected to

the transverse ducts and the inner portions of each of the supports being thermally connected to the axial ducts.

4. Refrigerating apparatus comprising, an elongated header for containing refrigerant, one or more loops extending from the header in an axial plane, and a plurality of loops extending from the header transverse to its axis and surrounding the first mentioned loops to form a freezing zone. 75

5. Refrigerating apparatus comprising, an elongated header for containing refrigerant, one or more loops extending from the header in an axial plane, a plurality of loops extending from the header transverse to its axis and surrounding the first mentioned loops to form a freezing zone, and two or more supports placed side by side in the freezing zone, the outer portions of each of the supports being thermally connected to the outer loops and the inner portions being thermally connected to the inner loops. 80

6. Refrigerating apparatus comprising, an elongated header for containing refrigerant, a relatively large number of ducts extending from the header and forming an inner freezing zone and an outer cooling space, and a relatively small number of ducts projecting into the freezing zone and having a relatively large area exposed to the freezing space, said latter ducts being arranged to divide said freezing zone into a plurality of compartments each adapted to receive an ice tray. 85

7. Refrigerating apparatus comprising, an elongated header for containing liquid refrigerant, one or more loops extending from the header in an axial plane, other duct means connected with the header, and means supported between said loop and duct means and in intimate metallic contact with the duct means and with a plurality of branches of the loop for supporting an ice tray. 100

8. Refrigerating apparatus comprising, an elongated header for containing liquid refrigerant, a plurality of duct loops connected with the header in parallel circuit relation, certain of said loops extending from the header in an axial plane, and other of said loops extending from the header transverse to its axis, and means supported between said loops and in intimate metallic contact therewith for supporting an ice tray. 110

9. A cooling unit for mechanical refrigerators comprising a rearwardly elongated header, heat exchange means connected with the header, one or more loops connected with the header, said loop being disposed below the header and extending rearwardly and cooperating with said heat exchange means to provide a horizontal and rearwardly extending freezing zone for an elongated ice tray. 115

10. A cooling unit for mechanical refrigerators comprising an elongated rearwardly extending header, heat exchange means connected with the header, one or more loops 120

connected with the header and disposed longitudinally thereof, said loop cooperating with said heat exchange means to provide a horizontal and rearwardly extending freezing zone for an elongated ice tray.

11. Refrigerating apparatus, comprising looped conduit means, the opposed branches of said looped conduit means forming therebetween a rearwardly extending freezing zone, and conduit means extending longitudinally of and within the freezing zone for dividing the same into a plurality of rearwardly extending freezing compartments for elongated ice trays.

12. Refrigerating apparatus comprising looped conduit means, the opposed branches of said looped conduit means forming therebetween a rearwardly extending freezing zone, ice tray supports disposed within said freezing zone and conduit means extending longitudinally of and within the freezing zone and disposed between and in thermal contact with said supports.

13. Refrigerating apparatus comprising looped conduit means, the opposed branches of said looped conduit means forming therebetween a rearwardly extending freezing zone, ice tray supports disposed within said freezing zone, and in different vertical planes, and conduit means extending longitudinally of the freezing zone and between and in thermal contact with the supports.

14. Refrigerating apparatus comprising a rearwardly elongated header for liquid refrigerant, looped conduit means connected with the header, the opposed branches of said looped conduit means forming therebetween a rearwardly extending freezing zone and conduit means extending longitudinally of and within the freezing zone for dividing the same into a plurality of rearwardly extending freezing compartments for elongated ice trays.

15. Refrigerating apparatus comprising a rearwardly elongated header for liquid refrigerant, conduit means connected with the header and providing a freezing zone, and conduit means extending longitudinally of and within said freezing zone for dividing the same into a plurality of rearwardly extending compartments each adapted to receive an elongated ice tray.

16. Refrigerating apparatus comprising a rearwardly elongated header for liquid refrigerant, conduits means connected with the header and providing a freezing zone, ice tray supports for rearwardly extending ice trays disposed within said freezing zone, and conduit means extending longitudinally of and within the freezing zone and disposed between and in thermal contact with said supports.

17. Refrigerating apparatus comprising a rearwardly elongated header for liquid refrigerant, conduit means connected with

the header and providing a freezing zone, ice tray supports for rearwardly extending ice trays disposed within said freezing zone, and in different vertical planes, and conduit means extending longitudinally of the freezing zone and between and in thermal contact with the supports.

18. A cooling unit for refrigerators comprising a header, a conduit connected with said header and extending longitudinally with respect to the axis of the header, a second conduit nested within said first named conduit and cooperating therewith to provide a row of conduits extending longitudinally with respect to the axis of the header, said row of conduits providing at least a portion of a wall of a freezing zone or compartment adapted to receive a receptacle to be cooled, and refrigerant conveying means communicating with said header and spaced laterally from said row of conduits to provide at least one other wall of said freezing zone or compartment.

19. A cooling unit for refrigerators comprising a header, a plurality of conduit loops disposed one outside of the other and having their ends connected with said header, said conduit loops being arranged to provide a row of conduits extending longitudinally with respect to the axis of the header to provide at least a portion of a wall of a freezing zone or compartment adapted to receive a receptacle to be cooled, and refrigerant conveying means communicating with said header and spaced laterally from said row of conduits to provide at least one other wall of said freezing zone or compartment.

20. A cooling unit for refrigerators comprising a header, a conduit depending from said header and extending longitudinally with respect to the axis of the header, a second conduit depending from said header cooperating with and nested within said first named conduit to provide a row of conduits extending longitudinally with respect to the axis of the header, said row of conduits providing at least a portion of a wall of a freezing zone or compartment disposed below said header adapted to receive a receptacle to be cooled, and refrigerant conveying means communicating with said header and spaced laterally from said row of conduits to provide at least one other wall of said freezing zone or compartment.

21. A cooling unit for refrigerators comprising a header, a plurality of conduit loops disposed one outside of the other and depending from said header, said conduit loops having their ends connected with the header and being arranged to provide a row of conduits extending longitudinally with respect to the axis of the header to provide at least a portion of a wall of a freezing zone or compartment disposed below said header adapted to receive a receptacle to be cooled, and re-

frigerant conveying means communicating with said header and spaced laterally from said row of conduits to provide at least one other wall of said freezing zone or compartment.

5 In testimony whereof I hereto affix my signature.

HAROLD B. WALLIS.
